UNITED STATES PATENT OFFICE.

PHELPS BROWN, OF SPRINGFIELD, AND IRA E. HENDRICKSON, OF WEST SPRINGFIELD, MASSACHUSETTS; SAID HENDRICKSON ASSIGNOR TO WICO ELECTRIC COMPANY, OF WEST SPRINGFIELD, MASSACHUSETTS, A CORPORATION OF MASSACHUSETTS.

MAGNETO.

Application filed December 3, 1926. Serial No. 152,487.

This invention relates to improvements in magnetos and has to do more particularly with features relating to the interrupter mechanism thereof.

- 5 The invention, according to one feature thereof, is directed to the problem of spark control in a particular type of magneto, viz., one in which the armature is moved into and out of contact with magnetic poles and in 10 which the armature may be moved away from its poles in either of two ways,—first entirely by an inelastic transmission of force from the engine and, second, initially by such transmission followed by an elastic transmission 15 from the expansion of previously stressed elastic means. The present invention offers as a solution to this problem mechanism whereby adequate control of the spark may be had with either form of armature drive. As much range of spark control 20 may be had as is desired whether the armature is moved away from its poles entirely by said inelastic transmission or partly by said elastic transmission.
- 25 Another feature of the invention relates to means for securing a variation in timing of the spark produced by the magneto by varying the position of what is ordinarily termed the fixed breaker point. One of the breaker 30 points is moved by, or under the control of, the armature and normally separates from its mating breaker point at a certain intermediate point in the flight of the armature away from its poles. By moving the other 35 breaker point, manually or otherwise, toward or away from the first named breaker point the separation of the points may be made to occur later or earlier in the flight of the armature.
- 40 The feature, just referred to, is desirable in any case because the particular breaker point in question, being light, presents much less resistance to movement and therefore a variation of its position may be effected much 45 more easily and with less cumbersome mechanism than can be effected with the other and armature operated point. Aside from this general advantage it permits, in a magneto of the type where both spring and direct in- 50 elastic drive are provided for moving the armature, a division of the spark control between these two forms of drive,—the position

of the upper breaker point being varied to provide for advance or retard of spark when direct drive is being used for the armature 55 and the control of the spark, when spring drive is used, being left to other means which vary the time when the armature leaves its poles.

The invention, in another of its broad aspects, relates to a magneto of the general type referred to in United States Letters Patent No. 1,634,135, granted June 28, 1927, to Phelps Brown. In such magneto, there are two magnetic circuits and two armatures 65 with mechanism for moving first one and then the other armature away from its poles and the E. M. F. produced by the flux change due to the movement of one armature away from its poles is merged with that produced by the 70 flux change due to the movement of the other armature toward its poles. The present invention offers a control for a magneto of this particular type in the nature of a single interrupter which causes the E. M. F. produced 75 by each unit to occur simultaneously.

The invention also has for another feature the provision of means for operating one of a pair of cooperating breaker points first from one armature and then from the other 80 armature of a magneto of the type disclosed in said copending application or in other magnetos of the dual armature type.

There are many other details which contribute to the accomplishment of the broad 85 purposes above set forth and these, together with other objects and advantages, will appear in the following description and will be pointed out in the appended claims.

The invention will be disclosed with reference to the accompanying drawings, in which:—

Fig. 1 is a front elevational view of a magneto embodying the invention,—the casing of the magneto being shown in section to reveal the interior;

Fig. 2 is an end elevational view looking from the left hand end of Fig. 1,—showing the magneto as it appears with the casing removed;

Fig. 3 is an exterior end elevational view looking from the right hand end of Fig. 1;

Fig. 4 is a cross sectional view taken on the line 4—4 of Fig. 1 but drawn to a larger scale;

Fig. 5 is a fragmentary cross sectional view taken on the line 5—5 of Fig. 1 but drawn to a larger scale;

Fig. 6 is a sectional elevational view taken on the line 6—6 of Fig. 2 but drawn to a larger scale;

Fig. 7 is a sectional bottom plan view taken on the line 7—7 of Fig. 1 but drawn to a larger scale;

Fig. 8 is a diagrammatical view illustrative of the electrical circuits and connections of the magneto;

Fig. 9 is a fragmentary sectional elevational view taken similarly to Fig. 6 but showing a modification in the spring support for the lower breaker point; and

Fig. 10 is a schematic view showing the control device positioned to effect spring drive of the armatures.

20 The magneto, illustrated herein, involves two units which are connected to work in co-operative relation so that each contributes to, and assists in, the work performed by the other. The two unit construction, while important and preferred, is not essential in so far as all features of the invention are concerned. Certain features of the invention, as pointed out in the appended claims are, or may be, entirely independent of the two unit arrangement.

These two units, as shown, are supported by a common frame, driven from a common drive shaft, utilize a common source of magnetic flux, and are controlled both mechanically and electrically from common means. These units, being alike, a description of one only will be necessary and the corresponding parts of the other unit will be designated by the same reference numerals primed.

40 Each unit includes a pair of cores 12 (Fig. 1), which are vertically disposed in spaced parallel relation and the upper ends of which are connected to opposite poles of a source of magnetic flux, herein exemplified by permanent bar magnets 13. The cores, of course, are built up from suitable laminations in the usual manner except that their upper ends are so shaped as to encompass the polar ends of the magnets and afford oppositely disposed recesses to receive the same. Between the laminations of cores 12 and those of cores 12' (the latter being located in back of but spaced from cores 12) are other laminations 14 (Figs. 2 and 6), which fill the space therebetween, as clearly shown in Fig. 2, and which are shaped correspondingly with the upper ends of the core laminations to afford magnet receiving recesses,—the whole affording two long, oppositely disposed recesses for receiving opposite polar ends of three stacks of permanent bar magnets. The magnets of each stack are held in place by wedges 15 which are driven in between two adjacent magnets of each stack and thereby force the upper and lower magnets of each stack firmly against the ends of

the receiving recesses in the laminations. The laminations of cores 12 and 12' and laminations 14 are suitably clamped together, as by a series of bolts 16. These bolts also act to secure opposite ends of non-magnetic cross bars 17 and 17' (Figs. 1 and 6) to the upper ends of cores 12 and 12', and these cross bars serve to hold the cores of each set in proper spaced relation. The lower ends of the cores, as shown in Figs. 1 and 7, are received in recesses formed in a horizontally disposed frame member 18 and are clamped in such recesses by screws 19. The cores extend downwardly a short distance below frame 18 and their bottom faces, which constitute magnetic poles, are adapted to be intermittently connected and disconnected by a reciprocating armature 20.

Each unit also includes two primary coils 21 (Figs. 1 and 7) encompassing each core 12, and two secondary coils 22, one encompassing each coil 21. The coils 21 and 22 and the corresponding coils 21' and 22' are housed in recesses formed in a common block 23 of bakelite or other similar or suitable material, which block fits snugly between frame 18 and the cross bars 17. The primary coils 21 may be connected in any suitable way to function as one choke winding. As shown in Fig. 8, they are connected in electrical series by a wire 24. The two choke windings, comprising the connected coils 21 and the connected coils 21' are controlled by a single interrupter comprising relatively movable breaker points 25 and 26. One terminal of each choke winding is grounded, as indicated in Fig. 8, and the point 25 which, as will appear, is in contact with metallic parts of the machine, is likewise grounded. The other terminal of each choke winding is connected by a wire 105 27 to the breaker point 26, which as will appear is insulated from the metallic parts of the machine. A condenser 28 is provided, one terminal of which is grounded and the other connected by a wire 29 to breaker 110 point 26.

The secondary coils 22, constituting the generating winding, are suitably connected, as in electrical series, by a wire 30 and the two generating windings, comprising the connected coils 22 and the connected coils 22' are connected in any suitable way so that the currents simultaneously produced in each are merged. As shown, the two windings are connected in series by a wire 31 so that the electromotive force produced in each is added. The terminals of the generating winding are connected to a suitable distributor D, which functions to successively connect the generating winding at properly timed intervals to a series of spark plugs 8.

The distributor, illustrated herein, involves an insulating panel 32 (Fig. 6) which is secured to one end of frame member 18 and carries four contacts 33 arranged in upper and

lower pairs. An insulating arm 34 pivoted to frame 18 at 35 (see also Fig. 3) oscillates back and forth between these pairs of contacts and carries conducting pieces 36 and 5 37 to simultaneously engage one contact of each pair. The two terminals of the generating winding are thus successively connected to pairs of spark plugs but the plugs of each pair are arranged in series and one of them 10 produces a spark on the firing stroke and the other near the end of the exhaust stroke. An insulating block 38, held in place by the casing C of the magneto, encompasses the contacts 33 and has sockets to receive the 15 spark plug wires 39 and carries springs 40 to connect such wires to the contacts 33. The construction and operation of the distributor is not essential to the present invention and is herein shown and briefly referred to merely 20 to complete the description and disclosure of the ignition apparatus.

The interrupter, referred to, is mounted near one end of the machine, being the end opposite from that at which the distributor 25 is located. The interrupter is supported from the center of a cross bar 41 (Fig. 5) which in turn is supported near opposite ends through the intermediary of spacing sleeves 42 from posts 43, formed integrally with and 30 standing from the frame member 18. Screws 44, passing through bar 41 and sleeves 42 are threaded into posts 43 and serve to clamp bar 41 thereto. The central portion of bar 41 has an opening therein into which a bushing 45 is tightly driven. This bushing slidably receives a tubular interrupter casing 46 which is provided exteriorly with upper and lower flanges 47 and 48. A spring wire 49, secured at its ends to bar 41 by the screws 40 44 described, is bent so as to afford two legs 45 extending vertically upwardly from the bar on opposite sides of casing 46 and a connecting horizontally disposed portion which is coiled around the casing. Upon this coiled portion rests the upper flange 47 of the interrupter casing, whereby the latter is normally held stationary in the illustrated position but can be moved downwardly when required, thereby stressing the spring 49 so 50 that the latter will subsequently, when permitted, return the casing back to the normal position. Means, later to be described, engage the lower flange 48 for the purpose of lowering casing 46.

55 The upper end of casing 46, which is closed, serves to support the breaker point 26—the latter being adjustably fixed to and insulated from said end. The other breaker point 25 is fixed to the upper end of a plunger 50 which 60 slidably fits the bore of casing 46. The plunger 50 is adjustably fixed to a threaded stem 51 the lower end of which has a flanged plug 51' (Fig. 6) to slip into a hole in the upper end of a hollow rectangular support 65 52. The latter is urged upwardly by a spring

53, which serves to hold plug 51' in its hole and which normally tends to hold breaker point 25 in engagement with its mating point 26. The breaker point 25 is in metallic connection with the frame 18 and therefore 70 grounded.

Referring now to the armature operating mechanism, the armature 20 is fixed by bolts 55 (Figs. 1 and 7) to an arm 56 and a plate 57,—the latter serving to move breaker point 75 25 as will later appear. The arm 56, at one end, is mounted on a stud 58, fixed to a post 59, which depends centrally from frame 18 and serves to support one end of the latter from and in spaced relation with a base plate 80 60. The other end of frame 18 is supported from base plate 60 by an end frame 61, which is secured by screws 62 (Fig. 2) to said end. The armature hinge arms 56 and 56' extend 85 along the inner faces of their armatures in parallel relation (Fig. 7) and beyond the armatures are offset outwardly and terminate with cylindrical ends 63 and 63', the axes of which are parallel. Such ends are disposed 90 closely adjacent the end frame 61.

Both the armature hinge arms 56 and 56' are operated from a common drive shaft 65, which is disposed between and slightly above these arms. The shaft 65 is rotatably mounted and adapted to be driven from an internal combustion engine and in proper timed relation therewith. In this particular case, it is adapted to be driven at crankshaft speed from a four cylinder, four cycle engine. The shaft 65 has a bearing near one end in the 95 end frame 61 (Fig. 6), an intermediate bearing in a lug 66 depending from frame 18 and a bearing near its other end in the post 59. The shaft extends beyond the latter and carries a cam 67 to actuate the distributor arm 34, 100 hereinbefore referred to. The shaft 65 has formed integrally therewith two cams 68 and 68' for operating the hinge arms 56 and 56' respectively. These cams are alike but diametrically opposed on shaft 65 (see Fig. 4). 105 They are also spaced one from the other longitudinally on this shaft although both are arranged in close proximity to end frame 61 (see Fig. 6). Each has a dwell portion of somewhat less than 180 degrees angular extent. The remaining portion of the periphery of each cam is made up of a rise portion and a drop portion,—these two portions gradually merging together as shown. The active portions of cams 68 and 68' are opposed 110 so that while one is functioning to move its armature away from its poles, the other cam permits the other armature to move back toward and into contact with its poles. The armatures 20 and 20' thus work substantially 115 in alternation although not in exact alternation.

The armatures may be moved in their flights away from their poles in either of two ways. 120 They may be moved entirely by an inelastic 130

transmission of force from their cams 68 and 68' or they may be initially moved a very short distance away from their poles in this manner and thereafter be moved the remaining distance by the expansive action of previously stressed elastic means.

The inelastic transmission is effected by the following mechanism. A lever 69 (Figs. 4 and 7) is mounted intermediate its ends 10 to turn freely on the cylindrical end 63 of the armature hinge arm 56. A cam follower, comprising an arcuate flange 70 bent outwardly at right angles from the free end of an S-shaped arm 71 of metal plate, is interposed between one end of lever 69 and its cam 68. The follower arm 71 is pivotally mounted on a stud 73 (Figs. 4 and 7) secured to a lug 74 on frame 61. In the case of the follower 71', the pivot stud 73' is secured to a post 75 which depends from frame 18 (Fig. 7). The lever 69, at its other end is provided with an adjustable abutment in the shape of a screw 76 (Fig. 4), designed to bear against the lower end of a pin 77, which is mounted 25 to slide freely in a lug 78 formed on frame 18. An armature return spring 72, (Fig. 6) interposed between armature 20 and base plate 60 tends to hold the armature to its poles and thus tends to raise the hinge arm 56 and the 30 lever 69 carried thereby, whereby the lever 69 is lifted, one end being caused to bear on pin 77 and the other end being caused to bear on follower 70, thereby urging the latter toward its cam 68.

35 The pin 77 may be held against upward movement beyond the illustrated position or, by adjustments to be described, it may be held against upward movement beyond certain other and higher vertical positions. When this pin 77 is held from moving upwardly beyond the illustrated position, a direct or inelastic drive of the armature 20 from cam 68 results. Thus, the pin 77 forms a fulcrum for lever 69 and, as the free end of the latter is depressed by cam 68, the hinge arm 56 is lowered and armature 20 is pried off its poles, to which it was theretofore held by the strong force of magnetic attraction, and moved away from its poles the required distance.

50 In order to hold the fulcrum pin 77 against upward movement beyond the illustrated position, or beyond various other and higher vertical positions, a cam 79 is arranged to bear on the upper end of pin 77, as shown in Figs. 1 and 4. This cam and the corresponding cam 79' are fixed to a shaft 80 near opposite ends thereof. This shaft, which extends transversely across frame 18, is seated in semi-circular bearings, formed in the upper ends of the described posts 43 and located forwardly of cross bar 41. It is held in each of these bearings by a strap 81, one end of which underlies the cross bar 41 (Fig. 6) and is upturned to bear against the same as a fulcrum. The strap 81 passes across the

top of shaft 80 and its other end is drawn downwardly by a screw 82 so as to create a friction on a shaft whereby easy or accidental turning of the same is resisted. The shaft 80 has fixed thereto a lever 83, whereby it may be turned to simultaneously move cams 79 to various positions of adjustment.

It will be noted that the cams 79 may be turned throughout a certain range (through the angle α shown in Fig. 10) without permitting a change in the vertical position of the fulcrum pins 77 and 77'. If moved beyond this range, the cams will permit these pins to be raised to various higher positions. When the cams are positioned, as last mentioned, the movement of the armatures away from their poles, after the preliminary prying off of the armatures by the inelastic transmission of force described, is effected by the expansive action of previously stressed elastic means. To secure this action, a drive spring 84 is interposed between a rearwardly offset lug 85 on lever 69 and an abutment 86, adjustably secured to cross bar 41 (Figs. 1 and 5). The abutment 86 has a long depending guide 87 extending into the spring to restrain it from undue transverse flexure and the abutment 85 has a projection 88 entering the lower end of the spring. It will be seen that, if pin 77 is free to rise above the illustrated position, the first action following the depression of cam follower 70 by cam 68 will be to tilt lever 69 about the cylindrical end 63 of the armature hinge arm as a fulcrum. This follows because the armature is held firmly to its poles by magnetic attraction and because the pin 77 is free to rise. Thus, the outer end of lever 69 is raised and the drive spring 84 is thereby placed under stress. This drive spring, even when stressed as much as possible with the illustrated arrangement, is insufficient to overcome the force of magnetic attraction which holds the armature to its poles. Consequently, the stressing of the drive spring continues until the pin 77 is arrested in its upward movement by cam 79. Then pin 77 functions as a fulcrum for lever 69 and the armature is pried off its poles by the described inelastic transmission of force from cam 68. Immediately following the prying off of armature 20 from its poles, the magnetic attraction on the armature is so diminished by the creation of even a very small air gap between the armature and its poles, that the previously stressed drive spring 84 is enabled to move the armature and more rapidly than it would be moved by cam 68. Consequently, spring 84 expands and, with the inner end of lever 69 temporarily serving as a fulcrum, moves the lever and thus the armature 20.

It will be obvious that the degree of stressing of the drive spring may be varied according to the position of pin 77, being greater if the pin is allowed to rise higher. It will also be obvious that the time when the armature

leaves its poles with relation to the angular position of shaft 65 may be varied by the setting of pin 77. When the latter is positioned as illustrated, the armature leaves its poles 5 at an earlier position in the revolution of shaft 65, or in what may be termed full advance position. If, however, the cams 79 be so set as to allow the pins 79 to rise above the illustrated position, the armature leaves 10 its poles at a later time in the revolution of shaft 65, or in what may be termed retard position. The production of a spark from the magneto depends on the time of separation of the breaker points 25 and 26 and such separation is effected by the movement of armature 20 and normally occurs after the armature has moved a certain distance away from its poles. Consequently, with the described 15 arrangement, a retarded spark is produced 20 from the magneto when spring drive is used and this is the desired condition for the spring drive is intended to be used primarily when the engine is started. By the use of other means, later to be described, the point 25 in the downward flight of the armature at which the breaker points open may be varied so that it is possible, should such a condition be desired to arrange for advanced spark when spring drive of the armature is used. 25

30 The mechanism for separating the breaker points 25 and 26 will now be described with particular reference to Figs. 5, 6 and 7. The plates 57 and 57', heretofore described as fixed to the armatures 20 and 20', extend beyond their armatures (to the left as viewed in Figs. 5 and 7) and the free end of each is given a quarter turn, thereby forming a horizontally disposed lug 90. Passing freely through the lugs 90 and 90', as best shown 35 in Fig. 5, are screws 91 and 91' which are disposed on opposite sides of the hollow rectangular support 52, heretofore referred to as carrying the breaker point 25. These screws also pass freely through a lever 92, one near each end thereof, and are supported from the lever by their heads which rest on crimped portions of the lever. This lever 40 92 encompasses the described stem 51 and centrally between its ends is fulcrumed on the upper face of the support 52 or strictly on the upper face of the flange of plug 51' which flange rests on support 52. The lever 92 is crimped at its middle to afford substantially the equivalent of a knife edge bearing to 45 form a suitable fulcrum and the crimped ends of the lever afford similar fulcrum bearings for engagement by the heads of screws 91 and 91'. These screws, below their respective lugs 90 and 90' carry adjustable abutments in the shape of nuts, 93 and 93', and lock nuts 94 and 94' to hold the abutments in their adjusted positions. 50

The arrangement described permits the one interrupter to be operated alternately by the 55 two armatures. As armature 20' left its

poles to reach the illustrated position the lug 90' eventually came into engagement with abutment 93' and tilted one end of lever 92 downwardly about its central crimped portion as a fulcrum, thus raising the other end 70 of lever 92 until abutment 93 engaged lug 90. After armature 20' had moved far enough away from its poles to take up all the slack in the connections described, further downward movement of armature 20' served to de- 75 press the support 52 and thus separate breaker point 25 from breaker point 26. The raised end of lever 92 then served as a fulcrum, bearing on the head of screw 91. The arrangement is such that the points 25 and 26 are separated at an intermediate point in the flight of armature 20' away from its poles. As armature 20' moves back toward its poles, the spring 53 causes the points 25 and 26 to be again engaged and just as the 85 armature 20' is about to seat on its poles 12', the armature 20 starts to leave its poles 12. The armature 20, in its flight away from its poles, causes lug 90 to engage abutment 93 and tilt the right hand end of lever 92 (Fig. 5) downwardly, raising the other end until all slack in the connections is taken up and thereby depressing support 52, with the raised end of lever 92 bearing as a fulcrum 90 on the head of screw 91'. Thus, the armature 95 20 also serves to separate the breaker points at an intermediate point in its downward movement. By suitable adjustment of the parts, the breaker points are caused to separate at the optimum point in the downward 100 flight of each armature.

It will be apparent that the breaker point operating mechanism described is characterized by an equalizing function. That is, the separate connections from each armature 105 to the breaker point 25 do not have to be carefully adjusted to a nicety to secure exact balance. This follows because the lever 92 in itself forms an equalizer. Inasmuch as both screws 91 and 91' function in each downward movement of the breaker point, a change in the effective length of one may be made without making a corresponding change in the effective length of the other and the breaker points will nevertheless open 115 at the same point in the downward flight of each armature. A change in the adjustment of one abutment nut, as 93, will vary the effective length of its screw 91 and affect a change in the time of operation of breaker 120 point 25 by armature 20 but the change will necessarily effect an equal change in the time of operation of the breaker point by armature 20'. 125

It has been shown heretofore wherein a change in the timing of the sparks from the magneto may be effected by changing the positions of cams 79 and 79', whereby the armature is caused to leave its poles at later 130 times when spring drive is used for the arma-

ture than when the latter is directly driven. It is often desirable to vary the timing when direct drive is used for the armature and for such purpose means are provided for varying the vertical position of the upper breaker point 26. Such means are preferably controlled from shaft 80 and, as shown in Figs. 4 and 6, a cam 95 is formed integrally with and on the central portion of shaft 80. Cam 95 is adapted to engage a rocker arm 96 pivotally mounted on a pin 97. Pin 97 is secured at its ends in laterally spaced depending ears formed on a washer like piece 98 which is held in place between the lower face of cross bar 41 and the flange of the described bushing 45. The inner end of rocker arm 96 straddles the interrupter casing 46 and bears against the flange 48. Consequently, when arm 83 is so turned as to cause cam 95 to lift the outer end of rocker arm 96, the inner end thereof forces flange 48 downwardly and causes breaker point 26 to be lowered. The lowering of point 26 naturally causes a later disengagement of point 25 therefrom. As pointed out before, spring 41 tends to hold breaker point 25 in its normal upper position and therefore acts to restore this breaker point when cam 95 is moved back into the position illustrated.

Referring to Fig. 10, it will be seen that shaft 80 can be turned throughout a certain range in which the breaker point casing 46, and thus the upper breaker point 26, can be moved without causing a change in the position of the fulcrum pins 77. Such range is designated by the angle α . When the cam 79 is turned so that line y coincides with the center line of fulcrum pin 77, the peak of cam 95 will engage the left hand rounded end of lever 96 and raise it into its uppermost position, thereby moving the upper breaker point 26 into its lowermost position. As cam 79 is turned counterclockwise through angle α , the cam 95 allows the breaker point 26 to rise and finally when cam 79 has been turned far enough to bring line z into coincidence with the center line of fulcrum pin 77, the breaker point will have been moved into its uppermost position. At such time, the left hand rounded end of lever 96 will be resting on the right hand side of cam 95, i. e., the side which is tangential to shaft 80. The opposite side of cam 95 is not exactly symmetrical with the side just referred to, the cam being widened out along this side, as indicated at 99. This side 99 is engaged by lever 96 during impulse drive, i. e., when cams 79 engage fulcrum pins 77 at some point in the angle b . It will be seen that under such conditions the upper breaker point 26 will be positioned at a level slightly lower than the uppermost position, which it occupies when the cams 79 are positioned for direct drive. During impulse drive, the tim-

ing of the spark is controlled by controlling the time when the armature is pried off its poles and the breaker point 26 is not required to move during such drive. It is necessary, however, that this breaker point 26 be properly positioned so that the movable breaker point 25 will separate from it at the optimum point in the downward flight of the armature and the part 99 functions to so position point 26. For impulse drive where the armature is driven by a spring always at substantially constant speed, there is one point in the downward flight of the armature where the best results are obtained and this point has been termed the "optimum" point. For direct drive, there is another factor which has to be taken into consideration, viz, the armature speed, and this factor is variable so that there will be no definitely fixed optimum point for all speeds. There will, however, be an "optimum" range of armature movement during which the breaker points should be opened to secure the most favorable results. That range will include the aforesaid optimum point as well as points on either side thereof. Thus, it is necessary that the cam 95 be arranged to move the upper breaker point 26 both above and below the fixed position which it occupies during impulse drive. Also, it is necessary to so move the breaker point 26 to secure timing of the spark by this particular method. That is, since the armature, when operated by direct drive, always leaves its poles at predetermined points in the revolution of drive shaft 65, the timing has to be effected in this instance by varying the point in the armature flight at which the breaker points are separated. Necessarily, when provisions are made for a range of spark advance, this means that the upper breaker point must be capable of being positioned above as well as at and below the point which it occupies on impulse drive, wherefore the non-symmetrical cam 95 is employed. By this arrangement, full retarded or full advanced spark can be obtained.

The upward pressure of spring 53 on support 52 is out of line with the vertical center line of the breaker point plunger 50, as will be apparent from an inspection of Fig. 6. To avoid this possible disadvantage, the arrangement shown in Fig. 9 may be used. As there shown, a support 100, corresponding functionally to support 52 but slightly different in shape, rests on the upwardly crimped bearing 101 formed on the free end of a lever 102 and between two spaced lugs 103 struck upwardly therefrom. The lever is pivoted at 104 to the bearing 66 and is urged upwardly by a spring 105 corresponding to spring 53 but located somewhat to the right of the position formerly occupied by spring 53. The arrangement shown in Fig. 10 permits the upward spring pressure to be ap-

plied to support 100 directly in line with the vertical axis of plunger 50.

In operation, as shaft 65 is revolved first one and then the other armature is moved. Each 5 armature moves through one cycle, that is, away from its poles and subsequently back into contact therewith, during a half revolution of shaft 65 and these cycles occur in alternation so that two sparks are produced 10 during each revolution of shaft 65 at symmetrical intervals. Thus, the magneto, when shaft 65 is driven at crank-shaft speed, will produce the ignition sparks necessary for a four cylinder, four cycle engine,—the ignition 15 E. M. F. from the magneto being distributed at proper intervals successively to the several cylinders by the distributor D, as above described. As one armature, say 20, moves away from its poles, the reluctance of its magnetic 20 circuit is greatly increased and when the breaker points 25 and 26 separate, the choking winding 21, which has theretofore tended to restrain a change of flux, is opened and a sudden change of flux results thereby generating an E. M. F. in coils 22. As the other armature 20' moved toward and into contact with its poles just prior to the downward movement of armature 20, the reluctance of the magnetic circuit of which it is a part was 25 also changed although a flux change was, to a large extent, restrained because the choke windings 21' were short circuited during the latter part of the return travel of armature 20'. The separation of breaker points 25 and 30 26 serves, as will be seen from Fig. 8, to open both the choking windings 21 and 21' so that two flux changes, one due to the downward movement of armature 20 and the other due to the upward movement of armature 20', are 35 produced and by the common control through the one set of breaker points these two flux changes are made to simultaneously produce two E. M. F.'s one in windings 22 and the other in windings 22'. These generating 40 windings are interconnected so that the two E. M. F.'s are merged. As shown, they are 45 added so that a better spark is produced by the two cooperating units than could be obtained with either when working separately.

The control of the two units of the magneto by a single set of breaker points constitutes 50 one feature of this invention.

Another important feature of the invention relates to the arrangement whereby one set of 55 breaker points may be operated first by one and then by another armature of a dual armature type magneto, whether or not that magneto is of the particular type disclosed in said copending application. As one armature 60 moves away from its poles, it rocks the operating lever 92 by means of the connecting screw, such as 91' and the other screw, such as 91, after it has been lifted until its abutment 65 93 engages the armature abutment 90, serves to anchor one end of lever 92 while the plunger 50 is lowered by continued downward movement of the armature, separating the breaker points 25 and 26. After the first named armature has returned to its poles and the other armature starts away from its poles, the plunger 70 50 will again be lowered to separate the breaker points in a similar manner except that the screw 91 will then serve to anchor the left hand end of lever 92, while the screw 91' will serve to pull it down. Thus, the one 75 interrupter is operated first by one and then by the other armature. It is particularly to be noted that the lever 92 serves as an equalizer and insures that the breaker points separate at the same time irrespective of which 80 armature operates them. After either armature has moved a definite distance away from its poles the points separate and the movement necessary for one armature to effect a separation of the points is the same as that 85 necessary for the other armature. Thus, as pointed out above, the necessity for fine and careful adjustments of the abutments 93 and 93' on their respective screws to secure nicely balanced action is eliminated. The arrangement is such that it inherently results in a nice balance without any attention whatsoever. The particular disposition of parts of the interrupter operating mechanism is also thought to be important for by locating some 90 parts above; others below, and others on opposite sides of the drive shaft 65, it is possible to apply the mechanism within the close limits of the small space available between the drive shaft and the two armatures and nevertheless have it function effectively and without interference with other closely adjacent parts.

The remaining features of the invention are independent of whether the magneto is of the dual armature type. Chief among these 95 features is the provision for varying the location of the upper breaker point 26, whereby the time of the separation of the breaker points may be varied to retard or advance the spark. This feature is important in any 100 case, regardless of the type of armature operating mechanism employed. The upper breaker point, not being subjected to any great stress, can therefore be movably supported for adjustment by parts of relatively 105 light construction which present less resistance to movement and enable the adjustment 110 to be effected while the magneto is in operation and with very little effort. This feature also is important in a magneto of the type 120 wherein both spring drive and direct inelastic drive are used for moving the armatures away from their poles. It enables a division 125 of the work of spark control between the two forms of drive and enables just as much control of the spark so far as retardation is concerned, whether direct or spring drive is used. When direct drive is used, the retardation of spark is effected by lowering the upper 130 breaker point, thereby causing the lower

breaker point to be disengaged from its mate at a later time in the flight of the armature away from its poles. When spring drive is used, the late spark is effected by delaying the time of initiation of the downward flight of the armature. The two means for spark control thus may be logically divided between the two forms of drive, providing all the spark control desired with either form of drive. A retarded spark with a spring drive of the armature is available for starting purposes and with direct drive there is available a full advanced spark or a fully retarded spark (as late as that available with spring drive) or various degrees of spark retard between the two extreme limits.

The invention has been disclosed herein, in an embodiment at present preferred, for illustrative purposes but the scope of the invention is defined by the appended claims rather than by the foregoing description.

What we claim is:

1. In a magneto, having two magnetic circuits including two sets of magnetic poles, reciprocable means forming part of said circuits for connecting first one and then the other of said sets of poles, a normally short circuited choke winding for each magnetic circuit, a generating winding for each circuit, a single set of relatively movable breaker points for simultaneously opening and subsequently simultaneously closing said choke windings, and means operable first from one armature and then from the other for separating said breaker points at an intermediate point in the flight of each armature away from its poles, and connections between said generating windings for merging the currents produced therein.

2. A magneto, comprising, two magnetic circuits each having a set of poles, a generating winding and a choke winding associated with each circuit, a reciprocable armature for each circuit to periodically connect and disconnect its set of poles, means for moving first one and then the other armature away from its poles, a single set of cooperating and relatively movable breaker points with yieldable means tending to hold them engaged, and means whereby each armature at an intermediate point in its flight away from its poles separates said breaker points, the latter being connected in a closed circuit with both said choke windings and when separated adapted to simultaneously open the same, and connections between said generating windings for merging the currents produced therein.

3. In a magneto, having two armatures with means for moving first one and then the other away from its poles, an interrupter comprising cooperating breaker points with yieldable means tending to hold them engaged, and means for each armature for moving one of said points away from the other

by and during the flight of each armature away from its poles, and an equalizer connection between both said means and the last named breaker point.

4. In a magneto, having two armatures with means for moving first one and then the other away from its poles, an interrupter comprising cooperating breaker points and yieldable means for holding them in engagement, a lever, a connection between one end of the lever and one of said armatures and a connection between the opposite end of the lever and the other armature, and a part movable with one of said breaker points, said lever being pivotally connected intermediate its ends to said part.

5. In a magneto having two reciprocable armatures operable substantially in alternation, an interrupter adapted to be operated alternately by said armatures, and comprising cooperating breaker points with yieldable means tending to hold them engaged, a sliding support to which one of said breaker points is fixed, a lever carried by and pivotally connected intermediate its ends to said support, connecting devices one for each armature depending from said lever and disposed on opposite sides of said support, an abutment on each armature through which its connecting device freely passes, and an abutment on each device adapted to be engaged by the corresponding armature abutment for separating said breaker points at a predetermined point in the movement of each armature.

6. In a magneto, having two sets of magnetic poles, an armature for each set movable into and out of contact therewith and means for moving first one and then the other armature so that during part at least of the flight of one armature away from its poles the other armature is in contact with its poles, a single interrupter having cooperating breaker points one of which is adapted to be moved away from the other first by one armature and then by the other during the flights of the armatures away from their poles, a member movable with said last named breaker point, a lever fulcrumed intermediate its ends thereto, and connections from opposite ends of said lever to said armatures, each of said connections serving as a fulcrum for said lever when its armature is in contact with its poles and while the other connection operates the lever during the flight of its armature away from its poles to separate said breaker points.

7. In a magneto, having two sets of magnetic poles and an armature for each set movable into and out of contact therewith, a drive shaft disposed between said armatures, an interrupter casing carrying a breaker point supported above said shaft, a cooperating breaker point slidably supported in said casing, a hollow support connected to move

- with said last named breaker point and loosely encompassing said drive shaft with freedom for vertical movement, a spring underlying said support for yieldingly holding 5 said breaker points engaged, a lever centrally and pivotally supported from the upper end of said support, a connection between one end of said lever and one armature, and a connection between the other end 10 of said lever and the other armature.
8. In a magneto, having two sets of magnetic poles and an armature for each set movable into and out of contact therewith, a drive shaft disposed between said armatures, 15 an interrupter casing carrying a breaker point supported above said shaft, a cooperating breaker point slidably supported in said casing, a hollow support connected to move with said last named breaker point and 20 loosely encompassing said drive shaft with freedom for vertical movement, a spring underlying said support for yieldingly holding said breaker points engaged, a lever centrally and pivotally supported from the upper 25 end of said support, headed members, one for each armature and disposed one at each end of said lever, said members passing freely through the lever and supported therefrom by their heads, abutments one for each armature and movable therewith through which abutments said members freely pass, and abutments one for each member and adjustably mounted thereon and each underlying 30 its armature abutment.
- 35 9. In a magneto of the type wherein an armature is moved into and out of contact with magnetic poles, and wherein a choking winding is arranged in an electrical circuit which can be opened and closed by a pair of 40 relatively movable breaker points, mechanism adapted for operation from an engine for moving the armature away from its poles, said mechanism including two relatively movable parts and a spring interposed 45 therebetween and adapted to be stressed by their relative movement, means for preventing relative movement of said parts and the stressing of said spring when desired and causing the armature to be moved away from 50 its poles solely by an inelastic transmission of force from the engine, means for moving one of said breaker points away from the other operable by movement of the armature and at an intermediate point in its flight 55 away from its poles, and means for moving the other breaker point to vary the point in the flight of said armature at which said breaker points will separate.
- 60 10. In a magneto of the type wherein an armature is moved into and out of contact with magnetic poles, and wherein a choking winding is arranged in an electrical circuit which can be opened and closed by a pair of 65 relatively movable breaker points, mechanism adapted for operation from an engine 70
- for moving the armature away from its poles, said mechanism including two relatively movable parts and a spring interposed therebetween and adapted to be stressed by their relative movement, means for preventing relative movement of said parts and the stressing of said spring when desired and causing the armature to be moved away from its poles solely by an inelastic transmission of force from the engine and at an earlier 75 time than when operated by said spring, means for moving one of said breaker points away from the other operable by movement of the armature and at an intermediate point in its flight away from its poles, and means for moving the other breaker point to vary the point in the flight of said armature at which said breaker points will separate. 80
11. In a magneto of the type wherein an armature is moved into and out of contact with magnetic poles, and wherein a choking winding is arranged in an electrical circuit which can be opened and closed by a pair of 85 relatively movable breaker points, mechanism adapted for operation from an engine for moving the armature away from its poles, said mechanism including two relatively movable parts and a spring interposed therebetween and adapted to be stressed by their relative movement, means for preventing relative movement of said parts and the stressing of said spring when desired and causing the armature to be moved away from its poles solely by an inelastic transmission of force from the engine and at an earlier 90 time than when operated by said spring, means for moving one of said breaker points away from the other operable by movement of the armature and at an intermediate point in its flight away from its poles, and means for moving the other breaker point to vary the point in the flight of said armature at which said breaker points will separate. 95
12. In a magneto of the type wherein an armature is moved into and out of contact with magnetic poles, and wherein a choking winding is arranged in an electrical circuit which can be opened and closed by a pair of 100 relatively movable breaker points, mechanism adapted for operation from an engine for moving the armature away from its poles, said mechanism including two relatively movable parts and a spring interposed therebetween and adapted to be stressed by their relative movement, means for preventing relative movement of said parts and the stressing of said spring when desired and causing the armature to be moved away from its poles solely by an inelastic transmission of force from the engine and at an earlier 105 time than when operated by said spring, means for moving one of said breaker points away from the other operable by movement of the armature and at an intermediate point in its flight away from its poles, and means for moving the other breaker point to vary the point in the flight of said armature at which said breaker points will separate. 110
13. In a magneto of the type wherein an armature is moved into and out of contact with magnetic poles, and wherein a choking winding is arranged in an electrical circuit which can be opened and closed by a pair of 115 relatively movable breaker points, mechanism adapted for operation from an engine for moving the armature away from its poles, said mechanism including two relatively movable parts and a spring interposed therebetween and adapted to be stressed by their relative movement, means for preventing relative movement of said parts and the stressing of said spring when desired and causing the armature to be moved away from its poles solely by an inelastic transmission of force from the engine, means for moving one of said breaker points away from the other operable by movement of the armature and at an intermediate point in its flight away from its poles, and means controlled by said 120 preventing means and operable when the 130

armature is moved solely by said inelastic transmission to vary the time of separation of said breaker points.

13. In a magneto of the type wherein an armature is moved into and out of contact with magnetic poles, and wherein a choking winding is arranged in an electrical circuit which can be opened and closed by a pair of relatively movable breaker points, mechanism adapted for operation from an engine for moving the armature away from its poles, said mechanism including two relatively movable parts and a spring interposed therebetween and adapted to be stressed by their relative movement, means for preventing relative movement of said parts and the stressing of said spring when desired and causing the armature to be moved away from its poles solely by an inelastic transmission of force from the engine, means for moving one of said breaker points away from the other operable by movement of the armature and at an intermediate point in its flight away from its poles, and means operable when relative movement of said parts is prevented to vary the position of the other breaker point to vary the time of separation of said breaker points.

14. In a magneto of the type wherein an armature is moved into and out of contact with magnetic poles, and wherein a choking winding is arranged in an electrical circuit which can be opened and closed by a pair of relatively movable breaker points, mechanism adapted for operation from an engine for moving the armature away from its poles, said mechanism including two relatively movable parts and a spring interposed therebetween and adapted to be stressed by their relative movement, means for preventing relative movement of said parts and the stressing of said spring when desired and causing the armature to be moved away from its poles solely by an inelastic transmission of force from the engine, means for moving one of said breaker points away from the other operable by movement of the armature and at an intermediate point in its flight away from its poles, and means controlled by said preventing means and operable when the armature is moved by said inelastic transmission to vary the position of the other breaker point to vary the time of separation of said breaker points.

15. In a magneto, wherein an armature is moved toward and away from magnetic poles, and wherein a normally short circuited choking winding is arranged to be periodically opened and subsequently closed by a pair of relatively movable breaker points, means operable during the movement of said armature away from its poles to move one of said breaker points away from the other to separate the same and open said windings, and means for moving the other breaker point

and holding it in various positions thereby to vary the point in said movement at which the breaker points separate and thus vary the timing of the spark from the magneto.

16. In a magneto, wherein an armature is moved into and out of contact with magnetic poles and wherein the production of the spark is controlled by the separation of a pair of relatively movable breaker points, driving mechanism including means for moving the armature away from its poles entirely by an inelastic transmission of force or in part by an elastic transmission of force, means controlled by movement of the armature away from its poles for moving one of said breaker points away from the other and for separating said points later when the armature is moved by an elastic transmission of force than when moved by the inelastic transmission of force, and means for moving the other breaker point to secure a range of timing of the spark when the armature is moved by an inelastic transmission of force.

17. In a magneto, of the type wherein an armature is moved into and out of contact with magnetic poles and wherein the armature may be moved away from its poles solely by an inelastic transmission from the drive shaft or partly by said transmission followed by the expansive action of previously stressed elastic means, a movable member effective during part of its movement to change from one form of transmission to the other, and means operable by said member during another part of its movement to vary the timing of the spark from the magneto.

18. In a magneto, of the type wherein an armature is moved into and out of contact with magnetic poles and wherein the time of production of the spark depends on the time of separation of a pair of relatively movable breaker points, driving means for moving the armature away from its poles solely by an inelastic transmission of force or partly by said transmission and partly by an elastic transmission of force, means for separating said breaker points at an intermediate point in the flight of the armature away from its poles, a movable member effective over part of its range of movement to vary the time of separation of said breaker points and over another part of said range to change the armature driving means from one form of transmission to the other.

19. In a magneto, of the type wherein an armature is moved into and out of contact with magnetic poles and wherein the time of production of the spark depends on the time of separation of a pair of relatively movable breaker points, driving means for moving the armature away from its poles solely by an inelastic transmission of force or partly by said transmission and partly by an elastic transmission of force, means for

- moving one of said breaker points away from the other at an intermediate point in the flight of the armature away from its poles, a movable member effective over part of its range of movement to move the other breaker point to vary the time of separation of said points and over another part of said range to change the armature driving means from one form of transmission to the other.
- 10 20. In a magneto, of the type wherein an armature is moved into and out of contact with magnetic poles and wherein the time of production of the spark depends on the time of separation of a pair of relatively movable breaker points, driving means for moving the armature away from its poles solely by an inelastic transmission of force or partly by said transmission and partly by an elastic transmission of force, means for moving one of said breaker points away from the other at an intermediate point in the flight of the armature away from its poles, a movable member effective over part of its range of movement to move the other breaker point to vary the time of separation of said points and when moved beyond said range to cause the armature to be moved away from its poles by said elastic transmission of force.
- 15 25. In a magneto, of the type wherein an armature is moved into and out of contact with magnetic poles and wherein the time of production of the spark depends on the time of separation of a pair of relatively movable breaker points, driving means for moving the armature away from its poles solely by an inelastic transmission of force or partly by said transmission and partly by an elastic transmission of force, means for moving one of said breaker points away from the other at an intermediate point in the flight of the armature away from its poles, a control member effective when moved a certain distance from one position to change the armature driving means from said inelastic to said elastic transmission and when moved less than said distance from said position to vary the position of the other breaker point to vary the time of separation of the breaker points and secure a range of spark control from full advance to full retard while the armature is being driven by said inelastic transmission.
- 20 25. In a magneto, of the type wherein an armature is moved into and out of contact with magnetic poles and wherein the time of production of the spark is dependent on the time of separation of a pair of relatively movable breaker points, means for moving the armature, means operable during an intermediate part of the flight of the armature away from its poles to separate said breaker points, and means operable while said armature is in motion for adjusting the position of one of said breaker points to vary the time of separation of the same.
- 25 23. In combination, a fixed guide, a member slidable therein and carrying a breaker point, a second member slidable in the first member and carrying a cooperating breaker point, means for periodically moving one of said members to carry one of said breaker points into and out of engagement with the other, and means for moving the other member to vary the time at which the breaker points will separate under the action of the first named means. 75
24. In combination, a slidably supported member carrying a breaker point, a second slidably supported member carrying a cooperating breaker point, means for periodically moving one of said members to separate and subsequently reengage said breaker points, and means for moving the other member to adjust the position of its breaker point and thereby vary the time at which the breaker points will separate under the action 80 of the first named means.
25. In combination, a fixed guide, a member movably mounted therein and carrying a breaker point, yieldable means tending to hold said member in a predetermined position, a second movably mounted member carrying a cooperating breaker point, means for periodically moving the second member to carry its breaker point out of and subsequently into engagement with the other breaker point, and means for moving the other member against the action of said yieldable means to vary the position of the other breaker point and thus the time at which the breaker points will separate under 90 the action of the first named moving means. 95
26. In a magneto, of the type wherein an armature which is movable into and out of contact with magnetic poles may be driven in its flight away from said poles either entirely by an inelastic transmission of force or initially by such transmission followed by the expansive action of previously stressed elastic means and wherein the time of production of the spark is dependent on the time of separation of a pair of relatively movable and cooperating breaker points, means operable to separate said breaker points during the flight of the armature away from its poles, shiftable means for changing from one form of armature drive to another, and means controlled by said shiftable means to cause said breaker points to separate at a different point in said flight of the armature when the latter is operated by one form of drive than 100 with the other. 110
27. In a magneto, of the type wherein an armature which is movable into and out of contact with magnetic poles may be driven in its flight away from said poles either entirely by an inelastic transmission of force or initially by such transmission followed by the expansive action of previously stressed elastic means and wherein the time of production of the spark is dependent on the time 115 120 125 130 of separation of the breaker points.
